PARTITION AND SUPPORT THEREFOR
FOR BEDS

Grace H. Randel, Brooklyn, N. Y.

Application May 18, 1949, Serial No. 93,894

4 Claims. (Cl. 5—329)

1

The invention comprehends a partition and base therefor, for the head areas of beds.

It is a well-known fact that occupants of a double bed are at times bothered by the irregular breath exhalations of their partners; that one or the other may have a cold, the sniffles, be subject to coughing spells, or the plain, everyday unpleasant breath that many humans are subject to. Additionally, one may wish to read, the other may not, and it is then desirable to have a partition to exclude the maximum of light, and have a measure of privacy.

An object of my invention is the provision of a hinged panel and base therefor which can be positioned at the head of a bed, the panel moved to and locked in vertical position when desired, and folded in parallelism with the support—flat, at will.

Another object of the invention is to provide a wall-like partition to separate the head regions of a bed, to keep the breathing areas of the occupants separate.

Another object comprehends a partition which can with ease and dispatch be changed from a vertical to a horizontal position.

A further object is a partition and base therefor which can be positioned under the pillows of a bed, will not be unsightly, or otherwise mar the appearance thereof.

Another and important object is the provision of a supported partition which includes therein a recess to fit over and accommodate the single top-most sheet of a bed and the superimposed blankets thereof, if the latter are in use.

Briefly described, the partition and base or support includes a sheet or blank of relatively rigid material, upon which is centrally and hingedly mounted a member adapted to be moved to vertical locked position and reversely to a position in parallelism with the support or base. On one lower edge of the partition I provide a recess or cutout portion for accommodating the confronting or meeting edge of the top sheet and, as the weather may dictate, the meeting edges of the superimposed blankets.

In the drawings:

Fig. 1 is a perspective view of a bed with the partition and support positioned with the latter underlying the pillows and the partition projecting vertically therebetween.

Fig. 2 is a top view of the invention illustrating the winglike conformation of the support and the forwardly projecting extension of the partition.

Fig. 3 is a top view showing the partition collapsed in parallelism with the support.

Fig. 4 is a side elevation of the partition and support.

2

Fig. 5 depicts a front elevational view showing the invention positioned with two pillows shown in outline.

The bed partition 5 comprises generally a base 6 with a continuous rear portion having a pair of winglike side extensions 7 and medially projecting portion 8 therebetween with tip 9. The base 6 forms a support upon which is centrally mounted, as by hinges 10, a vertically extending partition 11, provided with a forward extension 12, projecting outwardly from and above the lower edge, forming an arcuate-shaped recess 13. The side extensions 7 form palms affording necessary support at the sides of the base together with the tip 9 to prevent tipping forwardly of the partition hereinafter described.

Contiguous the lower edge 14 of the partition 11 opposite to that on which hinges 10 are mounted, and on top of base 6, I affix a molding 15 which abuts said lower edge and affords a snug fit when the partition 11 is in upstanding position. On the inner or rear of molding 15 is provided a snap fastener 16 cooperating with catch 17 attached to the partition for detachably securing member 11 vertically positioned.

When it is desired to drop partition 11 to flat position superimposed on base 6, fastener 16 is depressed and said partition lowered assuming the position shown in Fig. 3.

As admirably depicted in Fig. 1 the bed partition base 6 may be placed beneath the pillows and when in use, with member 11 vertical, the sheet and superimposed blankets may be extended with their upper edges drawn across the top of the bed and accommodated under the forward extension 12 in recess 13 thereunder. The extension 12, forming part of the partition 11, affords the maximum desirable privacy in the head region of the bed, and recess 13 precludes any undue disturbance of the bed coverings.

The partition and support are preferably fabricated from such relatively stiff materials as plywood, plastics or any other materials which might have the desired structural characteristics. The invention may be decorated, as by painting, veneering, or a covering which would aesthetically blend with and enhance the decorative ensemble of the bed and bedroom. Plastics, for example, may be furnished in different colors, to merge with the room color scheme.

When the partition is not in use, as previously explained, or in flat position, it is positioned under the pillows and when the bed is made, in the daytime, it is out of sight.

I reserve the right to make such changes and modifications as may come within the scope of the appended claims.

I claim:

1. A partition and base therefore for the head areas of beds including a base having a central portion with wing-like palms extending in opposite directions therefrom, said central portion having a projection provided with a tip, a partition including a body portion having one edge hinged to the central portion of the base, said partition having a forward extension projecting outwardly from the body portion, and means for locking the partition in a vertical position, the said forward extension of the partition projecting forwardly and outwardly above said tip when the partition is locked in vertical position.

2. A partition and base therefor for the head areas of beds, including a base having a central portion with wing-like palms extending in opposite directions therefrom, said central portion having a projection provided with a tip, partition including a body portion having one edge hinged to said central portion of the base, said partition having a forward extension projecting outwardly from the body portion, an arcuate recess between the tip and the forward extension, and means for releasably holding the partition in vertical position.

3. A partition and base therefor for head areas of beds, comprising a base having a central portion with a pair of wings extending from opposite sides of the central portion, said central por-

tion having a laterally extending projection, a partition having one edge hinged to the central portion of the base, said partition having a forward extension projecting outwardly from the body portion thereof, a molding attached to the central portion of the base in a position to about one edge of the partition, and means to releasably hold the partition in vertical position.

4. A partition and base therefor for the head areas of beds, including a base consisting of a single blank of material having a central portion with wings extending therefrom, said central portion having a projection, a partition having one edge hinged to the central portion of the base, said partition having a forward extension projecting outwardly from the body portion, an arcuate recess between the one edge and the forward extension for accommodating the top ends of bed covering.
